UNITED STATES PATENT OFFICE.

ROBERT K. ISERI, OF SACRAMENTO, CALIFORNIA.

SET OF BOOKKEEPING-RECORDS.

1,271,167.

Specification of Letters Patent.

Patented July 2, 1918.

Application filed June 2, 1917. Serial No. 172,430.

To all whom it may concern:

Be it known I, ROBERT KICHIKI ISERI, a subject of the Emperor of Japan, residing at Sacramento, in the county of Sacramento and State of California, have invented new and useful Improvements in Sets of Bookkeeping-Records, of which the following is a specification.

This invention relates to a set of records for account keeping covering the period from the time the recorded transaction is made until the final disposition thereof; and has for its object to enable the user, even though lacking in previous training as to bookkeeping, to keep a close and accurate account of his business. The entry of items is more or less automatic, which insures that the books will be kept up to date, and is largely mechanical so that the liability of mistake is remote.

In its present embodiment the set comprises a charge or credit sheet to be filled out generally in duplicate when sales are made or credits entered, or other transactions recorded, which sheet is provided with a plurality of detachable strips, each strip being properly ruled with journal or ledger columns on which the totals appearing on the main body of the sheet are entered at the time the transaction occurs. These sheets are preferably gummed and perforated. One is detached and pasted in a ledger book under the customer's account and the other is detached and placed in a journal representing the day's business, and a third one may be included to contain the total of the customer's daily balance, and this, when detached, is pasted in a daily balance book. The credit sheets and their associated strips are made either wider or narrower than the sales or charge sheets and strips, so that when detached and pasted in proper position in the ledger and journal the credit items will fall into a column to one side of the charge items, or as an alternative this may be accomplished by placing the columnar lines at different relative positions upon the sheets. The strips, when pasted and properly arranged in the ledger and journal, represent a complete account of the merchant's business which is totaled and balanced in the usual way.

One form which my invention may assume is exemplified in the following description

and illustrated in the accompanying drawings, in which—

Figure 1 shows an original and duplicate sales slip embodying my invention.

Fig. 2 shows an original and duplicate credit slip embodying my invention.

Fig. 3 shows a page of a journal on which detachable strips from the credit or sales bills have been pasted.

Fig. 4 shows a ledger sheet having the strips from said sales or credit sheets pasted therein in proper order.

Fig. 5 shows a page of a daily balance book made up of detachable strips pasted in proper position thereon.

Fig. 6 shows a sheet of an invoice book provided at one side with detachable and adhesive strips.

Referring now in detail to the set of records shown on the accompanying drawings, there is shown an original charge sheet 75 10, in the form of a sales slip, accompanying which is a duplicate sheet 11. The original sheet is adapted to contain entries of goods sold, interest, discount and freight charges in connection therewith, and is to be kept 80 indefinitely by the merchant, the carbon copy being delivered to the customer with the goods.

The original sheet contains at its lower edge three strips 12, 13 and 14, perforated 85 from each other and from the main body of the sheet. The first strip 12 is intended to show the balance of the customer's account to date and is ruled accordingly. The second strip 13 is ruled with ledger columns and on it the date, name of purchaser, and the amount of the purchase are entered. The third strip is ruled in journal columns and contains data similar to the second strip. The three strips, together with the main body of the sheet, are preferably serially 90 numbered for identification. Said strips are gummed on their back surface or otherwise supplied with an adhesive substance and when detached the first one is intended to be pasted on a sheet 15 of a daily balance book, as shown in Fig. 5. The second strip 13 is pasted in the proper position on a sheet 16 of a ledger under the account of the customer to whom the goods have been charged. 95 The third strip 14 is pasted in proper position on a sheet 17 of a journal, such as shown in Fig. 3.

The set includes record sheets for credit items which are entered on credit bills 18, such items representing amounts which may become due on account of goods purchased, 5 credits for goods returned, or money paid on account, interest, discount, freight and other miscellaneous items. The credit sheet is preferably printed in ink of a different color or on a differently colored paper from the charge 10 or debit sheet and is made somewhat wider or narrower. This credit bill may also have a duplicate 19 and is provided at its lower edge with detachable and gummed strips 20, 21 and 22, similar to the detachable strips 1b described in connection with the sales slip 10. The detaching and pasting of these strips are carried on in the same manner as already described, the first one going into the daily balance book, the second into the 20 ledger, and the third into the journal. By reason of the fact that these strips are either longer or shorter than the charge strips the amounts of the items appearing thereon will fall in a column to the right of the column 25 formed by the charge items.

When corresponding strips have been detached from all the charge and credit sheets used during any given period and properly pasted, the balance shown by the daily balance book will agree with the total amount 30 of the account sales of the ledger. The original sheets 10 and 18, from which have been detached the strips at the bottom, may be kept in index files or loose leaf forms for 35 future reference.

The invoice sheet 23, shown in Fig. 6, comprises right and left-hand divisions, the former made up of detachable and gummed strips 24 and the latter being merely the 40 ordinary form of ruled lines. Each division is provided with suitable journal or ledger columns for date, name, index number and amount and the amounts are entered in single entry fashion. Goods bought on account, goods returned, bills paid and items 45 of interest, discount, freight, etc., are entered here, first on the left-hand side and then extended to the right-hand side. The filled-in strips at the right are then detached 50 and pasted in the ledger to the debit or credit of the account involved. The left-hand division remaining shows a collective account of purchases and like items, such as 55 is generally provided for in any bookkeeping system.

By having the detachable and gummed strips associated with the collective invoice sheets, the items intended for the ledger can be entered at the same time and thus the 60 posting will be done mechanically and without danger of omission or error.

To illustrate the manner of using this set of account books, assume customer "A. White" comes in, pays \$20.00 on account and 65 buys \$2.20 worth of goods. A credit strip

for \$20.00 is made out (Fig. 2), the duplicate 19 is delivered to the customer and the original 18 is laid away. A charge strip (Fig. 1) is then made out for \$2.20, duplicate 11 is delivered and the original 10 filed. 70 At the close of the day the strips are detached from the filed original sheets and pasted in that book of the set which is specified at the left edge of each strip; in the journal (Fig. 3) chronologically; in the 75 ledger (Fig. 4) under the proper account. When the ledger strip is pasted in, the balance to date for the account in question is computed and entered, which entry is also made on the "daily balance" strip 12 (Fig. 80 1), which is then pasted in the daily balance book (Fig. 5), over the last prior strip of the same customer.

The labor and difficulty of bookkeeping are greatly increased by failure to keep the 85 books up to date. Those who do not employ expert bookkeepers are prone to let the work of posting, balancing, etc., fall behind until a considerable mass of detail has accumulated. Any system, therefore, which reduces 90 the time and labor of posting the items, although requiring at the time of entering the original transaction the notation of additional items, is a practical solution of the problems confronting the merchant who 95 does his own bookkeeping. With the present system the few seconds' time required to fill out the detachable slips, when the transaction occurs, will not be noticeable; yet the 100 fact of their having been filled out and detached will practically insure their being pasted in the proper position within the permanent books. When the items are in proper place and accurately posted the work of obtaining the necessary totals and balances requires but a few moments' time, and if this be done at the close of each day's business the books will always be complete and 105 up to date.

Various changes in the construction and 110 arrangement of the several parts herein shown and described may be employed without departing from the spirit of my invention as disclosed in the appended claims.

Having thus described my invention, what 115 I claim and desire to secure by Letters Patent is—

1. A bookkeeping set which comprises charge and credit sheets appropriately ruled and designated, each of said sheets having 120 detachable strips ruled with ledger and journal columns to be filled out with the totals of the debits or credits represented by the main body of the sheet at the time of the transaction, said strips being gummed on 125 their back surface for pasting in a ledger or journal, with the credits in one column and the debits in another.

2. A bookkeeping set which comprises charge and credit sheets appropriately ruled 130

and designated, each of said sheets having detachable strips ruled with ledger and journal columns to be filled out at the time of the original transaction, with the totals 5 of the debits or credits appearing on the main body of the sheet, said strips being arranged to be secured in place in the ledger or journal, the credit strips being of different length than the debit strips to bring their 10 respective items in different columns when placed in alinement.

3. A bookkeeping set which comprises charge and credit sheets appropriately ruled and designated, each of said sheets having 15 detachable strips ruled with ledger and journal columns to be filled out at the time of the original transaction, with the totals of the debits or credits appearing on the main body of the sheet, there being one strip 20 for ledger entries and one for journal entries on each sheet.

4. A bookkeeping set which comprises charge and credit sheets appropriately ruled and designated, each of said sheets having 25 detachable strips ruled with ledger and journal columns to be filled out at the time of the original transaction, with the totals of the debits or credits appearing on the main body of the sheet, there being one strip 30 for ledger entries and one for journal entries on each sheet, and said strips being gummed on their back surfaces to permit them to be pasted into position within the journal and ledger.

5. A bookkeeping set which comprises charge and credit sheets appropriately ruled and designated, each of said sheets having 35 detachable strips ruled with ledger and journal columns to be filled out at the time of the original transaction, with the totals of the debits or credits appearing on the main body of the sheet, there being one strip 40

for ledger entries and one for journal entries on each sheet, and said strips being gummed on their back surfaces to permit them to be pasted into position within the journal and ledger, the strips on the credit sheets being of different length than the strips on the debit sheets to bring their 45 respective items in different columns. 50

6. A bookkeeping set which comprises charge and credit sheets appropriately ruled and designated, each of said sheets having detachable strips at their bottom margin to be filled out at the time of the original 55 transaction, one of said strips being ruled with ledger columns and intended to receive the total of the items represented on the main body of the sheet, the other being appropriately ruled to receive the balance to 60 date of the account of the customer to whom the sheet is addressed, said strips being arranged to be secured one in a ledger and one in a daily balance book.

7. A bookkeeping set which comprises 65 charge and credit sheets appropriately ruled and designated, each of said sheets having a detachable strip at its bottom margin ruled and designated to receive the balance to date of the account of the customer to 70 whom the sheet is addressed, said strips being gummed and adapted to be pasted in a daily balance book when detached, subsequent strips referring to each customer's account being pasted over those already in 75 place and representing his previous balance.

In testimony whereof I have hereunto set my hand in the presence of two subscribing witnesses.
